CONTACT ROLL CONSTRUCTION

Robert J. Stock, Aspinwall, and John McLay, Leechburg, Pa., assignors to Allegheny Ludlum Steel Corporation, Brackenridge, Pa., a corporation of Pennsylvania

Application April 10, 1950, Serial No. 155,056

3 Claims. (Cl. 191—1)

This invention pertains to a new and improved contact roll construction for electrolytic treatment apparatus and particularly, for continuous treatment of strip metal wherein an improved distribution of current flow is obtained.

One phase of the invention relates to an improved contact roll construction and utilization for electrolytic treatment of strip metal and another phase relates to a construction for providing a more efficient and effective current flow in an electrolytic treating apparatus and particularly, in an electrolytic plating apparatus.

In the electrolytic plating of strip metal, such as strip steel, one or more continuous lengths of the material may be drawn from pay-off reels, through a wiper, an anodic cleaning tank, a rinse spray and scrubber, an acid pickling tank, a rinse spray and scrubber, a strike tank, a plating tank, rinse and spray tanks, a dryer, a powdering apparatus, a pulling unit, and finally to coiling reels. In one or more of these steps, the stock material may be subjected to electrolytic treatment. For example, in the copper plating of steel strip, an electrolytic strike tank and a plating tank require the application of current to the strip to produce the requisite flow for providing, in the case of the strike tank, a preliminary light copper plate or coating in a cyanide bath and in the case of the plating tank, a higher current for the full application of the copper to the requisite thickness on the surface of the material.

In plating line as well as in electrolytic cleaning line, it has been customary to use contact rolls which serve as a conducting means for current flow between the strip and an anode or cathode. Considerable difficulty has been encountered in providing electrical connections to the contact rolls for supplying current to the strip material. Heretofore, it has been customary in a pull or tension line to employ hollow or cylindrical rolls provided with steel end hubs and end shaft portions extending therefrom to which branches of a current-conducting bus bar are connected adjacent roll end bearings to supply current to opposite longitudinal ends of the rolls. Due to the rotation of the rolls, means must be provided for insuring efficient slip contacts between the opposite shaft portions and the bus bar branches. Due to the fact that roll shaft portions carry the current, care must be taken to avoid flash-over damage to the bearings.

The strip must make a tight contact with the rolls to prevent burning of the strip and this places an additional mechanical stress on the rolls. As a result, it has been customary to make the end connections to the rolls through steel hub portions, rather than through bronze or copper portions which are more efficient from a current-conducting standpoint. Our investigations have indicated that a contact roll provided with end electrical connections has a poor efficiency and provides a non-uniform electrolytic action transversely across the width of one strip or across one strip as compared to another, where a number of strips are carried by the same roll. We have determined that the efficiency of the electrolytic action decreases from the ends of the contact roll towards its center.

In today's operations, it is vital to obtain very thin coatings in a plating operation or to remove thin coatings in a cleaning operation to keep costs down and to avoid waste of the material involved. Requirements as to coating thicknesses are at the present time rather rigid

2

and variations between a series of strips being carried, or along the width of a single strip, gives rise to expensive rejects.

In copper coating steel strips, for example, we have found that the variation in coating thickness may be from .196 to .220 across the width of the strip or strips being plated. Supplying six volts at the generators, the voltage drop in the bus bars and the roll has been approximately 2.5 to 3.5 volts, giving an effective contact voltage at the roll of about 3.5 to 2.5 volts. Such a voltage drop (about 50%) heats up the roll and the bus bar branches and increases wear and tear on the slip connections to the roll. In fact, the heat becomes so great that it has been customary to "hose" the bus bars down from time to time with cold water. The poor electrical characteristics of such a construction have also necessitated slowing down the line, so that at least a minimum thickness of coating can be obtained.

In investigating this matter, we found that direct current tends to hug the ends of the contact roll and as a result, a strip located centrally on the roll receives a much lighter coating or treatment than a strip located adjacent an end thereof. There does not appear to be a good flow of current from the ends of a roll towards its intermediate portion and further difficulty is encountered by reason of the two end connections. That is, one end connection may be more efficient than another or may offer less resistance to current flow than another and stray currents will flow therebetween, thus setting up an additional voltage drop and further heating the rolls and the bus bar connections.

It has thus been an object of our invention to provide a new and improved contact roll construction for electrolytically treating metal material such as strip;

35 A further object has been to provide a contact roll construction that is more effective in conducting electric current to a metal strip being electrolytically treated;

A still further object has been to provide a new and improved form of contact roll construction and connections thereto;

These and many other objects of our invention will appear to those skilled in the art from the following description and the illustrated embodiments thereof.

In the drawings Figure 1 is a vertical section taken longitudinally of an electrolytic striking bath employing contact rolls of our invention;

Figure 2 is an enlarged end sectional view in elevation through a contact roll of our construction and taken along the line II—II of Figure 1;

50 Figure 3 is a fragmental view in elevation taken from the right end of Figure 2 along the line III—III thereof;

Figure 4 is an enlarged sectional detail of spring-pressed, slip contact brushes.

We have been able to solve the problems heretofore presented and particularly, the problem as to contact roll connections by providing a contact roll to which an electrical connection is made centrally thereof, intermediate its ends, and through non-ferrous, highly conductive material. This also overcomes previous limitations in the rate of movement, or the effective rate of electrolytic treating which may be successfully employed for the strip material. It makes possible a substantially uniform transverse distribution of treating action along the width of the material during its longitudinal movement, a minimized voltage drop, and avoids excessive heating of the bus bars, the roll, and other current conducting portions. It makes possible an elimination of flash-over to roll bearings.

70 By using the improved contact roll construction of the present invention, we have cut the voltage drop down to about one volt (utilizing a six volt source), have eliminated dangerous or appreciable heating, and have minimized wear and tear on the bus bars and the other parts. We provide a direct, highly conductive, non-ferrous connection to the contact roll, since the connections no longer have to be made through ferrous metal to provide the requisite mechanical strength. We get a new and improved current flow distribution along the length of a contact roll which is from the center of the roll towards its end. Such flow is enhanced by the normal tendency

of the current to concentrate at the ends of a contact roll. By using a single contact with the roll, we avoid stray currents that are set up by counter-voltages, and enhance and improve the effective flow of current along the length of the contact roll.

In a contact roll of our construction, the maximum variation in the depth of a plated coating produced on the material along a roll of about 6 ft. in length is now about .196 to .195; this is about half the minimum variation of about .196 to .220 that is possible using a conventional roll construction. Coil runs of about 45 to 50 tons can now be easily effected in a 24 hour period as compared to a previous maximum of about 27 to 30 tons, using a tank width of about 60 inches. In addition, cooling means for the bus bars is no longer necessary.

In the illustrated embodiment of our invention, we have shown contact rolls in a plating line each of which is supported by end closures or hubs of ferrous metal. Each roll has a non-ferrous or copper contact hub or ring positioned centrally or intermediate its ends which is brazed or soldered thereto and has a non-ferrous shaft or bar extending through one of the end hubs, past its end bearing to carry a non-ferrous metal commutator or cylindrical contact wheel. A bus bar from the generator is connected to a bus bar squirrel cage which supports spring-loaded brushes that ride on the cylindrical surface of the commutator or contact wheel.

For the purpose of illustrating our invention, we have shown equipment which is connected for effecting a plating operation, such as for applying a copper coating to steel strip. The strip may be a single width strip corresponding to the width of the contact rolls or, as is more customary, may be a series of narrow-width strips positioned in a transversely spaced-apart relationship on the contact rolls and drawn from coils in line through treating apparatus and when the treatment is finished, recoiled at the other end of the line.

Our invention relates particularly to a new and improved form of contact roll construction. To illustrate a use of our roll construction, we have shown apparatus employed in an electrolytic striking (see Figure 1).

Referring to Figure 1, a strip 10 is carried over a contact roll at position A. The roll 11 is shown positioned with its lower portion extending slightly into a water tray 12 to keep it moist. The strip 10 is supplied with current of negative potential by the contact rolls 11 at positions A and B that represent opposite longitudinal ends of a striking bath metal container 16 and is guided substantially longitudinally therethrough by a pair of end-mounted, submerged guide rolls 13. The container 16 may be filled with a suitable striking liquid, such as copper cyanide, and has an inner, non-conductive coating or layer 17, such as of a rubber that is resistant to the bath liquid. The container 16 is mounted on longitudinal and transverse beam members 14 and 15 and carries an electrode metal catch and support tray 19. The tray 19 rests upon wood or other insulating cross members 18 to space it and position it with respect to the bottom of the container 16. A pair of vertical upright pieces 25 are secured to side flanges of the tray 19 at opposite longitudinal ends thereof and are secured to a pair of longitudinally-extending bus bars 26 to form an electrode frame construction. A series of cross rods 27 are secured in a spaced-apart relationship along the bus bars 26 and serve as hanger bars for a plurality of removable electrode hooks 28.

As shown particularly in Figure 1, electrodes 29 are adapted to rest in the lower portions of the hooks 28 and to be supplied with positive current where the bath is used for a preliminary or striking plating operation. The tray 19 has a protective, non-conductive, inner coating 17 and serves to catch any electrode material falling away from the hooks 28 and to support scrap electrode material therein. In this manner, electrode material is positioned on opposite sides of the strip 10 as it moves through the bath container 16.

In Figures 2 and 3, we have shown details of the construction of our new form of contact roll. This roll has a cylindrical portion 57, preferably of a ferrous metal such as steel; a non-ferrous, highly conductive connector hub 58 is securely positioned within its bore intermediate its ends. The bore of the cylinder 57 is planed or machined out at 57b to permit the insertion of the hub 58 from the right hand end of the roll and the seating of it within an offset bore portion 57a. When the hub 58

has been positioned as shown in Figure 2 and the ends of the roll cylinder 57 are still open, the cylinder is positioned to stand on its left hand end, and a highly conductive soldering material, such as Silfoss, is poured in along an end groove 58a to flow downwardly between the flange portion of the hub and the bored-out seat 57a of the cylinder. The solder builds up at 59a to provide a strong, but highly electrically efficient metal-to-metal contact between the hub 58 and the internal bore 57a of the cylinder 57. The cylinder 57 may be heated to effect this operation.

The hub 58 has an internal bore which receives a reduced end portion 60a of a conductor bar or shaft 60. The conductor shaft 60 is mounted within the bore of the hub 58 preliminary to the insertion of the hub within the cylinder 57 in substantially the same manner as outlined in securely-electrically connecting the hub to the cylinder. The conductor shaft or bar 60 is also of non-ferrous, highly conductive metal construction. After the hub 58 has been secured with its shaft 60 in the position shown in Figure 13, end or closure hubs 61 and 61' may then be mounted in position within the cylinder. As shown, the end hub 61 is of similar construction to the end hub 61', except that the latter has a slightly different size bore. Thus, a description of the end closure 61 will suffice. The hubs 61 and 61' are of ferrous metal such as steel to provide requisite mechanical strength for the roll construction. A strip line is ordinarily drawn under high tension over a series of rolls including contact rolls during its processing. Thus, friction must be minimized and such rolls must have a high mechanical strength to withstand the forces involved.

The end closure or hub 61 (61') has a circular front flange and a welded-on (see weld 62a) circular back flange 62 which are adapted to slide within an enlarged bore seat portion 57c of the cylinder 57 and to be secured thereto by weld metal 61a. The right hand closure hub 61 is securely feathered or mounted and inset on a portion 63a of a steel sleeve shaft 63 which extends outwardly along the conductor shaft 60 in a spaced-apart relationship with respect thereto. The sleeve shaft 63 extends through a suitable bearing unit, such as a Jones-Timken pillow block box or unit 64 and at its outer end portion 63c carries a circular support flange 65 securely inset thereon. The flange 65 is of annular shape and is adapted to carry an electrical contact wheel or commutator 68. The sleeve shaft 63 is adapted to rotate with the conductor bar or shaft 60, but is segregated and held in an electrically, non-conducting relationship with respect thereto by insulating circular end pieces 64a that are mounted within inset bore portions 63b at its opposite ends. The pieces 64a may be of Micarta or other suitable insulating material and extend about the conductor shaft 60.

A cone-shaped wedge member 69 has a cylindrical internal bore which is adapted to rest upon and make good electrical contact with the conductor shaft 60 at its outer end. The wedge member 69 has an outer tapered or cone-like periphery which cooperates with a similar bore periphery 68a of the contact wheel 68 and is mounted thereon by adjustable bolts 70, so that the tightness of fit between the wheel 68 and the shaft 60 can be adjusted as desired. The wheel 68 and the wedge member 69 are both of non-ferrous, highly conductive metal and the former has an outer periphery of planar-cylindrical shape to serve as a surface for spring-pressed slip or slide contact brushes 71. The wheel or commutator 68 is secured to the support flange 65 by bolts 67 which are mounted in insulating sleeves 66 and on insulating washers to prevent current from flowing from the wheel 68 to the sleeve shaft 63 and thus, to the bearing box or unit 64 within which it is journaled.

In Figure 4, we have shown an enlarged sectional detail of spring-pressed contact brushes 71 such as employed in motors and generators which may be used in this connection and which are carried by a series of backwardly-projecting mounting bracket arms or members 72. A U-shaped, upright member or end bracket 74 that is positioned on insulation 75 and is secured by bolts 75a through insulating sleeves and washers to a base member 76. The base member 76 is welded to extend from a supporting I beam 77. Electrical bus straps 81 are at their upper ends secured as by soldering or brazing to the front end of a non-ferrous stud 79 that extends forwardly from a back wall portion 74a of the bracket 74. Bus

straps 80 of U-shape are also secured to the front end of the stud 79 and extend backwardly therefrom. The back or inner ends of the straps 80 are secured by bolt and nut assemblies 73 between the mounting brackets 72 and the back wall portion 74c of the bracket 74 to supply current by a plurality of short paths to the brushes 71. As shown particularly in Figure 3, the conductor straps 80 are formed into somewhat of a squirrel cage arrangement and connect directly at their ends to the six brush-mounting brackets 72. Since all of the members from the bus bar straps 81 to the hub 58 are of non-ferrous, highly conductive metal, such as copper, bronze, etc., it will be apparent that a highly efficient, low resistance path is provided for current flow from the bus straps 81 to the intermediate portion of the roll 11 to which electrical connection is made. It will also be apparent that no current flows directly through the sleeve shaft 63, the bearing units 64, or through the closure hubs 61 and 61' from the bus bar straps 81.

The closure hub 61' at the other end of the roll 11 is secured on a stud shaft 85 that is carried by a pillow bearing unit 64. It will be noted that a splash member 78 is positioned beneath each bearing unit 64 and that each unit is mounted on the upper flange of the I beams 77 through insulation pieces 75. In the case of the left hand unit 64, a metal spacer member 84 is provided.

Ordinarily, about six volts is sufficient and it will give an effective plating voltage at the contact roll surface of about five volts. The starting amperage may be about 20,000 total with the intermediate rolls carrying about 5,000 amps. each and the end roll pairs carrying about 6,000 amps. each.

Previous to our invention, the width of strip which could be effectively treated was limited. For example, in a plating operation a poor coating was obtained with a width a strip of 18 inches and this constituted the absolute maximum width dimension. Now, employing our invention, an 18, 20, or wider inch strip can be substantially uniformly coated in an effective manner without any difficulty. In accordance with our invention, we provide an intermediate connection to each contact roll 11 through non-ferrous parts. Furthermore, the tendency of direct current to hug the ends of the rolls is utilized in obtaining an efficient flow of current towards such ends without the counter-flow currents incident to the previous method of connecting each roll end to the supply of current. This is a problem which has been long outstanding in the art and on which many millions of dollars have been spent by others in an attempt to solve it.

What we claim is:

1. An improved contact roll construction which comprises, a hollow cylindrical contact roll of ferrous metal having a good mechanical strength, a pair of strong ferrous metal end hubs secured within opposite end portions of said roll for rotation therewith, a strong ferrous metal end shaft extending outwardly from each of said hubs and secured thereto for rotation with said hubs and said contact roll, external bearings at each end of said contact roll rotatably mounting said end shafts, one of said end shafts being a sleeve shaft having an open end bore therealong, an electrically-conductive non-ferrous metal connector hub positioned centrally within said contact roll intermediate its ends and having its outer peripheral surface secured to and in an efficient electrical conducting relationship with an inner peripheral surface of said roll for rotation therewith and providing an exclusive electrical

current connection with said roll, an electrically conductive non-ferrous conductor bar positioned in a peripherally spaced relation within and along the bore of said sleeve shaft and having inner and outer end portions extending longitudinally through opposite ends of said sleeve shaft, annular insulating pieces set within the bore of said sleeve shaft in engagement with said conductor bar to hold it in a substantially centrally-aligned spaced and non-conducting relationship with the bore of said sleeve shaft, the inner end portion of said conductor bar being secured within said connector hub in an efficient electrical conducting relationship therewith, and electrical contact means of non-ferrous metal construction securely mounted on the outer end portion of said conductor bar and secured through insulating means to the outer end portion of said sleeve shaft for rotation therewith.

2. An improved contact roll construction as defined in claim 1, wherein said contact means comprises an electrically conductive non-ferrous metal contact wheel 20 mounted in adjustable-wedging and electrically-conductive engagement on the outer end portion of said conductor bar, and wherein a mounting means for said contact wheel comprises a support secured on the outer end portion of said sleeve shaft and adjustably secured through 25 said insulating means to said contact wheel.

3. An improved contact roll construction which comprises, a cylindrical contact roll of strong ferrous metal construction, a pair of strong ferrous metal end hubs secured within and closing off opposite ends of said contact roll and having separate strong ferrous metal shaft portions extending outwardly therefrom, bearings at each end of said roll rotatably mounting said shaft portions, an electrically-conductive non-ferrous metal connector hub secured centrally within said roll intermediate its ends and providing an exclusive electrical conducting path thereto, a highly conductive non-ferrous metal conductor bar extending through one of said shaft portions into said connector hub and being secured in an efficient electrically-contacting relation thereto, said conductor bar extending outwardly through said one shaft portion in a peripherally spaced-apart relationship with respect thereto, insulating means positioned between said conductor bar and said shaft portion adjacent opposite ends of said shaft portion, an electrically-conductive non-ferrous contact wheel about an outer end of said conductor bar, an electrically-conductive wedge-shaped sleeve mounting said contact wheel on said conductor bar and having means to adjust said sleeve axially along said contact wheel, a ferrous metal mounting flange secured to and projecting from an outer end of said one shaft portion, and means securing said mounting flange to and electrically insulating said flange from said contact wheel.
